RIBBON EDGED BRAID

Filed June 21, 1928

FIG. 1

FIG. 2

Joseph Havel

INVENTOR

BY
Robert B. Killgore
ATTORNEY

UNITED STATES PATENT OFFICE.

JOSEPH HAVEL, OF NEW YORK, N. Y., ASSIGNOR TO JOS. BRANDT & BRO., OF NEW YORK, N. Y., A COPARTNERSHIP COMPOSED OF JOSEPH BRANDT, LOUIS BRANDT, AND ABRAM BRANDT.

RIBBON-EDGED BRAID.

Application filed June 21, 1928. Serial No. 287,177.

My invention relates to braids edged with ribbon-like material to be used in hat making, for trimming and the like, and it is my object to produce a braid which will, when made up into a hat be firm and yet have the appearance of being made of ribbon-like material and yet not be so stiff that it cannot be used as a trimming.

The drawing is a greatly enlarged view 10 of the braid, for clearness of illustration. Fig. 1 is a plan view of a hat braid having ribbon-like material on one edge; and Fig. 2 is a diagrammatic view of the braid with ribbon-like material along both edges. 15 The braid comprises a plurality of flat tapes 1, 2 and 3, which are preferably loosely woven of nitro-cellulose threads, although any relatively stiff material which yields a tape of strength and lightness, may be employed. The tapes are braided together in 20 the ordinary manner into a flat braid. As the tapes are braided together in the braiding machine a ribbon-like material 4 such as ribbon, braid, a narrow strip of nitro- 25 cellulose material, or the like, is wound round and round the outside turns of the tape as illustrated. In the form shown in Fig. 1 the ribbon-like material extends along one edge. If desired a second piece of ribbon-like material 5 may be wound around 30 the outside turns on the other edge as shown in Fig. 2.

If the braid of Fig. 1 is to be made up into a woman's hat the lap will come with the braids under the ribbon-like material 35 and the latter will be exposed on the outside so that the hat will appear to be made of twisted ribbon-like material and still be firm enough to hold its shape, which would not be the case if ribbon-like material alone 40 were employed.

In the double edged form of Fig. 2 the tape may be used as a dress trimming or ornament as it is flexible enough to be bent and follow curves and turns. 45

I claim:—

1. As a new article of manufacture, a braid comprising a plurality of flat tapes of relatively stiff material braided together into a flat braid and a piece of ribbon-like 50 material wound round and round the outside turns at one edge thereof.

2. As a new article of manufacture, a braid comprising a plurality of flat tapes of relatively stiff material braided together 55 into a flat braid and a pair of pieces of ribbon-like material each wound round and round the outside turns at opposite edges thereof.

In testimony whereof I have affixed my 60 signature.

JOSEPH HAVEL.
